UNITED STATES PATENT OFFICE.

DANIEL WILLIAM NASH, OF EASTLAKE, ALABAMA, ASSIGNOR OF ONE-THIRD
TO JAMES BOREUGARD GIBSON, OF WOODLAWN, ALABAMA.

FOUNDRY-LADLE.

SPECIFICATION forming part of Letters Patent No. 619,431, dated February 14, 1899.

Application filed March 16, 1898. Serial No. 674,026. (No model.)

To all whom it may concern:

Be it known that I, DANIEL WILLIAM NASH, a citizen of the United States, residing at Eastlake, in the county of Jefferson and State 5 of Alabama, have invented certain new and useful Improvements in Foundry-Ladles; and I do hereby declare the following to be a full, clear, and exact description of the invention, such as will enable others skilled in the art 10 to which it appertains to make and use the same.

My invention relates to improvements in foundry-ladles in which an interior cylinder is placed forming a receptacle to receive the 15 molten metal from the cupola; and the objects of my improvement are, first, to provide a foundry-ladle with an internal cylinder to form an inner receptacle to receive the metal from the cupola; second, to provide 20 proper facilities to elevate or raise the interior cylinder from the ladle bottom to allow the metal to escape therefrom to the ladle; third, to provide a foundry-ladle with an interior receptacle adapted to be raised from 25 the ladle bottom to allow the metal to flow therein, the slag and cinder being retained in the receptacle. I attain these objects by the mechanism illustrated in the accompanying drawings, in which—

30 Figure 1 is a top view of a foundry-ladle having my improved slag-separator attached thereto. Fig. 2 is a vertical sectional view of the same through the center. Fig. 3 is an enlarged detail vertical view of the elevating 35 and clamping device with the connecting-arm attached to the interior cylinder. Fig. 4 is a vertical cross-section of the same through the center.

Similar numerals refer to similar parts 40 throughout the several views.

The foundry-ladle 1 as shown represents the form of ladle in general use. The outer shell is made of suitable metallic material, the shell being lined on the inside with fire-clay 2 45 in the usual manner. My device can be used on any other form of ladle desired.

The internal cylinder 3 can be made of any desired metallic material, a series of spurs 4 being formed on the outside near the lower 50 end, the spurs extending outward to nearly fit the ladle. The metallic cylinder is covered

with fire-clay 5 in the usual manner to protect the same from the molten metal. The connecting-arm 6 is attached to the head of the internal cylinder in any desired manner. 55 The arm extends at a right angle from the cylinder to the edge of the ladle, at which it is bent to extend downward on a vertical seat formed on the side of the ladle. The downwardly-extending shank of the arm is provided with a circular aperture 7, and an oblong aperture 8 is formed therein.

The stud 9 is rigidly attached to the ladle side. The stud extends through the circular aperture formed in the arm-shank. An eccentric cam 10 is mounted on the stud, the cam engaging the aperture formed in the shank. A flange 11 is formed on the outer edge of the cam, and a handle 12 is attached thereto to operate the cam. The nut 13, having a handle 14, is attached by screw-threads to the outer end of the stud 9. The nut when screwed up presses the cam-flange on the arm-shank and holds the same rigidly to place at any desired position. The stud 15 is rigidly 75 attached to the ladle side. The stud extends through the slot-aperture formed in the arm-shank. A key 16 is inserted in the end of the stud to hold the shank to place.

In operation, the molten metal is run from 80 the cupola to enter the receptacle formed in the center of the ladle. The slag and cinder, being lighter than iron, will float on the surface of the metal. The center receptacle when raised by the action of the cam will allow 85 the metal to flow under the lower edge thereof and enter the ladle, the slag remaining in the receptacle. The cleaned metal in the ladle can then be poured in the molds and the operation repeated as often as desired. 90

The ladle when turned for pouring, brings the lip thereof below the level of the inner receptacle, and the metal pours from the ladle in the usual manner, a sufficient amount of metal being retained in the ladle at each pouring to keep the inner receptacle sealed and prevent the slag entering the ladle. 95

Having thus described my invention, what I claim as new, and desire to secure by Letters Patent, is—

1. The combination with a foundry-ladle of a hollow bottomless cylinder placed therein

and arranged to seat on the bottom of the ladle, thereby forming an inner receptacle therein, the connecting-arm attached thereto and extending downwardly on the outside of the ladle, with means to raise the inner receptacle from the bottom of the ladle, substantially as and for the purpose described.

2. The combination with the ladle of the hollow bottomless cylinder placed therein and arranged to seat on the bottom of the ladle, the connecting-arm attached to the head there-

of and having an apertured stem extending downwardly on the outside of the ladle, the eccentric cam operating in the aperture formed in the arm-stem, and the nut to clamp the cam, substantially as described.

In testimony whereof I affix my signature in presence of two witnesses.

DANIEL WILLIAM NASH.
